QUENCHING DEVICE FOR HEAT-TREATING APPARATUS

Howard E. Somes, Detroit, Mich., assignor to Budd Induction Heating, Inc., Philadelphia, Pa., a corporation of Michigan

Original application September 17, 1937, Serial No. 164,320. Divided and this application January 20, 1942, Serial No. 427,485

3 Claims. (Cl. 266—6)

This application is a division of my copending application, Serial No. 164,320, filed September 17, 1937, patented April 28, 1942, No. 2,281,331, and the subject matter divided therefrom relates in general to quenching apparatus for use in heat treating articles hardenable by heating and quenching.

The primary object of the invention is the provision of an improved quenching head which is extendable to a quenching position within a tubular member which has been heated to a hardening temperature.

Another object is to provide a quenching apparatus with a quench discharging head which is extendable from a retracted non-operative to an extended operative position in quenching relation with an article heated to a hardening temperature through the medium of a fluid motor means, the fluid for actuating such motor means being the same fluid as that employed for the quenching operation, thus providing a simplified and economical construction in which assurance is had that the quenching fluid can be discharged only when the quench head is in its proper position for quenching the heated article.

In the drawings which illustrate the quenching apparatus shown in my parent application aforesaid:

Figure 1 is an elevational view of the apparatus, a portion of the same being shown in section to illustrate the quenching apparatus;

Figure 2 is an axial section taken substantially at right angles to the view shown in Figure 1; and

Figure 3 is a fragmentary view similar to Figure 2 showing the quench head in an extended operative quenching position.

Referring to the accompanying drawings, in which like numerals refer to like parts through the several views, the apparatus is mounted upon a suitable base 10 and is carried by a vertically adjustable work carriage or platform 11 provided with a vertically movable work holder 12 for holding the workpiece in an axially vertical position. The workpiece here shown for the purpose of illustration is a tubular member 13 with respect to which the bore 14 thereof has been heated and is to be quenched by the apparatus now to be described.

The carriage or platform 11 is slidably mounted on a pair of uprights 15 forming part of the base 10, and is arranged to be moved upwardly and downwardly by a pair of elevating screws 16 which may be driven in any suitable manner.

As shown in detail in Figure 1, the platform 11 carries the vertically movable work holder 12

which is mounted for movement thereon by means of a plurality of guide rods 17 slidably mounted in tubular guide members 18 provided on the platform 11. The work holder 12 is supported on the upper ends of the rods 17 through shouldered extensions 19 which slidably extend through openings 20 in the holder 12 thus enabling various interchangeable work holders provided with like arrangements of openings 20 to be employed in place of the holder 12, so that workpieces of different diameters may be treated with the same apparatus.

The rods 17 are connected at their lower ends for movement as a unit by a yoke member 21 which is arranged to be raised and lowered by a work cylinder 22 supported by the lower central part of a well 23 formed in the platform 11. This work cylinder is provided with a piston 24 which is fixed to a tubular shaft 25 keyed to the central portion of the yoke against axial movement relative thereto. Connections to the interior of the shaft 25 for admitting and discharging operating fluid at opposite ends of the piston 24 are provided through suitable pipe connections 27 and 28 which extend to a suitable fluid control mechanism, not shown.

The quenching apparatus is supported through the medium of a tubular member 29 mounted within the tubular shaft 25. This member 29 which is counterbored from its lower end to provide an enlarged bore 31, extends axially beyond the end of the central portion of the yoke 21 as clearly shown in Figure 2. The extending end of the tubular member 29 is closed by a cap 30 having a guide rod 31 supported thereby to extend axially within the tubular member 29 in circumferentially spaced relation. The guide rod 31 is formed at its upper end with a short bore 31a and ports 32 opening therefrom through the wall thereof.

The cap 30 is surrounded by an annular member 33 to provide an annular chamber 34 therewith. A conduit 35 connected with a suitable source of quenching fluid, not shown, is provided for introducing quenching fluid into the chamber 34, the chamber 34 communicating with the interior of the tubular member 29 through a plurality of passages 36.

The quench member comprises a tubular rod 38 closed at its upper end and provided adjacent this end with any desired number of quench discharge openings 39. This rod extends through the tubular member 29 with its lower end surrounding the guide rod 31 in slidably telescoping relation, the intermediate portion of the rod 38 having a sliding

fit with the upper reduced portion of the bore. It is to be noted that the lower end of the rod 38 is provided with a piston 40 engaged with the enlarged bore 37 and that a coiled compression spring 41 is interposed between this piston and the end 42 of the enlarged bore 37 to urge the piston and attached rod 38 to a lowermost or retracted position, this being the non-quenching position. It is to be noted also that in this lowermost position the rod 38 covers the ports 32 in the guide rod 31 to prevent communication through these ports between the quenching fluid space surrounding the quench rod 38 and the internal passage of the same.

In the lowermost position of the quench rod 38, the upper or nozzle end thereof is disposed below the workpiece 13 carried by the work holder 12, as shown in Figure 1, so that the bore of the workpiece may be heated in any suitable manner, such as that described in my copending application aforesaid.

After the workpiece is heated to the desired temperature and the heating apparatus removed from within the bore thereof, quenching fluid is admitted to the chamber 34 through conduit 35 under pressure and this quenching fluid enters the enlarged bore 37 of the tubular member 29 through the passage 36 where it acts against the piston 40 to raise the quench rod 38 to an extended position against the resistance of the spring 41, this extended position being shown in Figure 3. The extended position of the quench rod 38 is predetermined by the engagement of the piston 40 with a shoulder 43 formed in the enlarged bore 37, and it is to be noted that the ports 32 in the guide rod 31 are not uncovered until the guide rod 38 reaches this extended position. As soon as the ports 32 are uncovered by the quench rod 38, the quenching fluid may thus flow into the ports 32 through the quench rod and thence into the discharge openings 39 for projection against the heated internal surface of the workpiece to be quenched. The ports 32 and the pressure of the quench fluid, of course, are such that the pressure of the quench fluid is sufficient to maintain the quench rod in its uppermost position.

I have thus provided a quenching apparatus and movable means for actuating the same to a quenching position which by reason of the fact that the quench fluid also serves as the medium for actuating the motor means provides for simplification of construction and operation of the apparatus. One advantage of the construction described is that the discharge of the quenching medium can take place only when the quench nozzle is in its proper position to perform an efficient quenching operation and not at some improper intermediate position. This is brought about by the fact that the supply ports 32 are not uncovered for flow to the nozzle openings 39 until the piston 40 is in its uppermost position, as

shown in Figure 3, which position predetermines the quenching position of the quench head or rod.

It is to be understood that while I have shown and described a certain specific embodiment and mode of operation of the present invention for the sake of illustration, the invention is not limited to such specific embodiment and mode of operation but contemplates such variants and modifications thereof as fall fairly within the scope of the appended claims.

What is claimed is:

1. In an apparatus for quenching a heated workpiece, a tubular rod having a quench discharge passage adjacent one end thereof, a piston and cylinder means associated with said rod for longitudinally moving said rod from a retracted non-quenching position to an extended quenching position, means for supplying quenching fluid under pressure to said piston and cylinder means to move said rod to said extended position, and valve means openable upon said rod reaching its extended position to establish communication between said piston and cylinder means and the interior of said rod for the flow of quenching fluid from said piston and cylinder means through said rod to said quench discharge passage.

2. In an apparatus for quenching a heated workpiece, a tubular support, a tubular quenching fluid-conducting rod longitudinally slidably mounted in said support, said support having a closed end and a guide rod extending into the adjacent end of said rod, said guide rod having a central passage and openings in the wall thereof, normally closed by said fluid-conducting rod in retracted position, said fluid-conducting rod having a piston cooperating with said support and forming a chamber with said support and closed end, and means for introducing quenching fluid under pressure into said chamber for moving said piston and fluid-conducting rod to an extended quenching position, said fluid-conducting rod uncovering said openings upon reaching said extended position to permit quenching fluid to flow from said chamber through said openings to the interior of said fluid-conducting rod.

3. In an apparatus for quenching a heated workpiece, a quench discharge member having a passage therein for quenching fluid and being movable from an inoperative non-quenching position to an operative quenching position, actuating means associated with said quench discharge member and being operative by quenching fluid to move said quench discharge member from inoperative to operative position, means for supplying quenching fluid under pressure to said actuating means, and means operable by the movement of said quench discharge member to operative position to conduct quenching fluid from said actuating means to said passage.

HOWARD E. SOMES.
